UNITED STATES PATENT OFFICE.

THOMAS H. STAMP, OF BUFFALO, NEW YORK.

HEATER FOR DOMESTIC BOILERS.

Application filed June 21, 1926. Serial No. 117,343.

This invention relates to the type of heaters designed more particularly for domestic water boilers and comprising a heat-confining jacket partly or wholly surrounding the boiler and having a burner in its lower portion for heating it.

One of the objects of the invention is the improvement of the heater with a view of keeping its outer side cool and at the same time holding the rising current of hot air closely against the boiler to heat it more effectually and in less time.

A further object is to so construct the heater as to effect complete combustion of the gas before being allowed to escape through the exit flue.

In the accompanying drawings:—

Figure 1 is a side elevation of a domestic water boiler equipped with the improved heater. Figure 2 is an enlarged vertical section of the heater applied to the boiler. Figure 3 is a horizontal section on line 3—3, Fig. 2. Figure 4 is a detached fragmentary side elevation of the supplemental heater. Figure 5 is a horizontal section of a modified form of the heater.

Similar characters of reference indicate corresponding parts throughout the several views.

10 indicates a domestic boiler of the usual cylindrical form. It may be mounted on the customary stand 11.

In the embodiment of the invention shown in Figs. 1-3, the heater consists of a segmental jacket or casing 12 of suitable height which extends around about one-third of the circumference of the boiler and is provided in its lower portion with a burner 13, preferably a gas burner, and at its top with an exit pipe 14.

20 The jacket is open at its inner side to expose the surface of the boiler directly to the flames of the burner and the ascending hot air; and, as shown in Fig. 2, the jacket is provided at its upper and lower ends with segmental rims 45 or bearing-faces 15, 16, which conform to and are tightly fitted against the side of the boiler and the upright edges of the jacket are likewise fitted against it to prevent the escape of the hot-air and products of combustion at

50 those points. The jacket is clamped to the boiler by a U-shaped belt or strap 16^a, or other means. Otherwise, the jacket is closed on all sides, excepting a horizontal row of air-inlets 17 in its lower portion just above the burner.

In its preferred form, the upper portion

of the jacket is contracted or tapered upwardly, as shown at 18, while its lower portion 19, which contains the air inlets 17 is enlarged beyond the radius of the body and the 60 base of the heater to provide an ample air and gas mixing chamber. The burner may be of any appropriate construction, that illustrated in the drawings consisting of a horizontal gas conduit or chamber 20 extending 65 throughout the base of the jacket and cast integral with it and provided in close proximity to the boiler-wall with one or more rows of openings 21 through which the gas issues in numerous jets directly against the boiler. 70 A gas supply pipe 22 having an air-mixer 23 of any suitable construction is connected to the burner-conduit.

Arranged in the heating jacket about midway between its wall and the wall of the 75 boiler is an imperforate upright partition 24. This partition is concentric with the wall of the jacket and preferably rises from about the horizontal center line of the air-inlets 17 to the base of the reduced top 18 of the jacket. 80 The partition forms with the jacket wall an outer non-conductive space or passage 25 through which the air entering the inlets 17 rises, keeping the outer side of the jacket comparatively cool. The space 26 between 85 the partition and the boiler form a hot-air flue, the partition confining the ascending current of hot air against the boiler, thereby obtaining the maximum effect and expediting the heating of the water to the required 90 temperature.

By extending the partition down to the air inlets 17 practically complete combustion of the gas takes place in the lower portion of the hot-air flue 26 adjacent to the gas burner, 95 with the result that the gas products are fully burned before reaching the top of said flue.

The partition, by forming this cooling flue, does away with the usual jacket-lining of 100 asbestos or other non-conductive material.

A water-circulating device 28 may be arranged in the hot-air flue 26, for heating the water in the boiler. For example, this device may consist of upper and lower manifolds 29, 30 connected by water-circulating tubes 31, the manifolds communicating with the boiler by pipe-connections 32, 33.

It has been found in practice that a segmental jacket, embracing about one-third of the circumference of the boiler, is sufficient to heat the water to the required temperature 110

in a relatively short time; but if desired, the jacket may be of greater extent, or of cylindrical form to completely surround the boiler, as shown in Fig. 5. In this case, two or more units or segments like that shown in Figs. 1, 2 and 3, are tied together and clamped against the boiler by horizontal bolts 34 or other appropriate fastenings.

I claim as my invention:

- 10 1. A heater of the character described, comprising a jacket open at its inner side and having bearing faces conforming to a water boiler, the jacket being provided in its base with a burner and having air inlets in its lower portion above the burner, and an imperforate upright partition arranged in

the jacket about midway between its outer wall and its bearing faces, forming an air passage between the jacket and the partition, the lower end of the latter terminating near 20 said air inlets.

2. A heater of the character described, comprising a jacket open at its inner side and having bearing faces conforming to a water boiler, the jacket having a burner and an exit, a partition in the jacket between its outer wall and its bearing faces disposed concentrically therewith, the jacket having air inlets in the lower portion of its wall, and water-circulating means located on the inner 25 30 side of said partition.

THOMAS H. STAMP.
